HOIST LIMIT MECHANISM

Frank Leck, Philadelphia, Pa., assignor to The
Yale & Towne Manufacturing Company, Stamford, Conn., a corporation of Connecticut

Application June 30, 1949, Serial No. 102,289

9 Claims. (Cl. 254—173)

1

This invention relates to a hoist, and more particularly to limit means for stopping the operation of the hoist when the load is raised to a predetermined position, relatively to the hoist. Mechanisms of the particular class are very old and are well known in the art. However, in general, the limit mechanisms of the prior art are either not positive, or else do not lend themselves to adjustment by movement of the load. Where the limit mechanisms are not positive, they are frequently ineffective with resulting damage. Where limit mechanisms are not readily movable by the load they are subject to rather considerable damage, it being possible to apply part of the lifting stress to the limit mechanism. Obviously, since the limit mechanism is merely designed to control the operation of the hoist, it cannot bear the stress of the load, so that it is frequently damaged.

As a feature of my invention, limit means are provided that are positive, and yet are adapted for ready movement with the load relatively to the hoist to which the limit mechanism is applied in a manner to avoid acceptance of lifting strains.

As a particular feature of the invention, I provide limit means that are readily movable with the load, the limit means being operable in all positions to which they are moved relatively to the hoist by the load. As a more particular feature of this part of the invention, I provide a chain guide that is adapted for sliding movement relatively to a support, the support being itself pivotally movable relatively to the hoist. For this reason, the chain guide is adapted for swinging movement with the chain as may be required. However, when the end of the chain and the usual hook strikes the chain guide, the chain guide is then movable relatively to its support to actuate the limit mechanism. Incidentally, while I use a chain as the load lifting medium, it should be understood that my invention applies equally well to other means such as a cable. The load chain should, therefore, not be considered as limiting my claims and invention.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my dis-

2

closure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is an elevation and partial section of a hoist showing my invention applied thereto. Fig. 2 is a section taken along lines 2—2 of Fig. 1. Fig. 3 is a view of certain of the parts of Fig. 2 in a second position. Fig. 4 is a side view of a part of the hoist assembly looking toward Fig. 2 from the left of said figure. Fig. 5 is a section taken along lines 5—5 of Fig. 2.

Referring now more particularly to the drawings, and especially Figs. 1 and 2, there is shown a conventional hoist utilizing a load sheave 10 adapted for rotation by the usual motor M carried by the hoist and suitable gearing G, all as is well known by those skilled in the art. In the particular hoist illustrated, I use a load sheave 10 cooperating with a chain 11 for moving that chain in opposed directions, a load hook 12 being attached to one end of the chain 11, and a second load hook 13 being attached to the other end of chain 11.

In actual operation, suitable control means are used for controlling the rotation of the load sheave 10 by the motor M so that when rotating in one direction, it will lift one of the load hooks while lowering the other hook, thereby lifting a load on one hook as the other hook moves downwardly. Upon reversal of rotation, the load sleeve 10 will actuate the chain 11 to lift that hook that has earlier been lowered so as to raise the load that may have been applied to the hook.

It naturally becomes important to stop the operation of the motor M when one of the hooks is moved to its extreme upper position, as for example, the hook 12 in Fig. 2. Where, as in the case of hook 12 in Fig. 2, the chain moves in a vertical plane, it is possible to use almost any positive type of limit mechanism to be contacted by the hook assembly when that hook assembly reaches its extreme upper position. Where the hook and chain are at an angle, as in the case of the right hand hook 13 of Fig. 2, due to the fact that the load is at an angle, means must be provided for allowing such movement of the chain and hook without destroying or damaging the limit mechanism. Thus, the limit mechanism should so be designed that it will be operated accurately and without strain or damage,

whether or not the load is lifted in a vertical plane as by the hook 12, or in an angular direction as by the hook 13. Through my contribution to the art, I provide limit mechanism that is correctly and positively operated regardless of the angular position of the chain in one plane thereof. It will be understood by those skilled in the art that the chain may move in two planes, but that in its movement in a plane at right angles to that of Fig. 2, it merely tends to tilt the hoist on its mounting means.

In my invention, the limit mechanism I have provided is duplicated at each side of the hoist. I shall describe the limit mechanism at one side of the hoist, it being obvious that it is unnecessary to duplicate the description. I provide a shaft 14 supported in bearings 15 on the hoist, and having pivotally mounted thereon a pair of opposed downwardly extending guide and support rods 16. Mounted on each rod 16 is a cylinder 17, a spring 18 being contained within each cylinder 17 and bearing at one end thereof against a shoulder 19 of shaft 16 while guided by a pin portion 19a formed at the end of each rod 16. Obviously, the springs 18 urge the two cylinders 17 downwardly relatively to the rods 16.

The two cylinders 17 are bored for opposed stub shafts 20 extending from a chain guide 21 and function thereby to support chain guide 21 for pivotal and sliding movement relatively to the hoist. Chain guide 21 is formed as seen best in Fig. 5 for guiding the chain links. Per se, this guide is not my invention herein claimed.

At one end thereof, one of the stub shafts 20 has pivoted thereto a lever 22 extending upwardly, lever 22 being pivoted at 23 to a further lever 24. Lever 24 is formed with a bored upper end 25 that is suitably keyed or splined to a shaft 26 extending into a switch housing 27. In the switch housing there is contained a controlling contactor 28 of any suitable construction equipped with a switch actuating plunger 29 adapted for coaction with a cam 30 at the end of the shaft 26. It is quite obvious that as the cam 30 rotates through movement of shaft 26 by levers 22 and 24, it will operate the plunger 29 to actuate the contactor 28 and to break the circuit of motor M and apply the usual brake.

In Fig. 2 the left chain guide is shown in that position in which it is normally maintained when a load is lifted vertically by normal actuation of the chain 11. Any additional vertical movement of the hook 12 by the chain 11 in Fig. 2 will, of course, effect vertical movement of the chain guide 21, the chain guide moving vertically through the accompanying movement of the cylinders 17 on the rods 16 against the resistance of springs 18. This movement of the chain guide 21 will effect movement of lever 22 and the switch operating lever 24 so as to rotate shaft 26 and its cam surface 30 and thereby operate the contactor 28 to break the circuit of the hoist motor.

At the right hand side of Fig. 2 the chain guide 21 is shown in that position to which it is moved by a load applied to the hook 13 with the load displaced vertically relatively to the hoist. It will here be noted that the levers 22 and 24 have been moved away from their normal position but that this has not in any way affected the operation of the limit switch mechanism. If now the hook is raised by the movement of the chain in the angular direction illustrated, the chain guide 21 will be moved to the dash and dotted line position of Fig. 2 with the switch operating lever 24 rotating the shaft 26 so as to

operate the contactor to break the circuit of the motor M of the hoist. It will be readily appreciated that during this movement there has been no strain whatsoever on any part of the limit operating mechanism.

In Fig. 3 one chain guide 21 is shown swung to the left of its normal vertical position by the displacement of the chain through the application of the load at the left of the vertical line. 10 If in this position of the parts the chain 11 is actuated to move the hook 13 upwardly and along the line of the chain, then of course the levers 22 and 24 will be actuated once again, as previously outlined, to break the circuit of the contactor 28. Again it is readily seen that there has been no strain whatsoever on the operating parts of the limit mechanism and that the said limit mechanism has been actuated most effectively.

It will now be appreciated that the operation of my limit mechanism is positive, because the hooks 12 and 13 contact their respective chain guides 21 in all positions thereof to effect operation of the levers 22, 24. It is further appreciated that while this action is positive, it is accomplished without imparting strain to the parts of the limit mechanism. Thus, all the force exerted on the chain guide is in a direction tending to move the chain guide in the normal manner for which it is adapted to move relatively to the rods 16 and with the cylinders 17. It is thought that the considerable merit of my invention will now be fully appreciated.

I now claim:

1. In a hoist of the class described, a hoist body, a chain guide, support means mounting said chain guide for pivotal swinging movement, means mounting said chain guide for sliding movement relatively to said support means, a switch actuating lever pivoted on said hoist body, and an operating member pivoted to said switch actuating lever and to said chain guide for moving said switch actuating lever upon sliding movement of said chain guide on said support means.

2. In a hoist of the class described, a hoist body, a chain guide, support means mounting said chain guide for pivotal swinging movement, means mounting said chain guide for sliding movement relatively to said support means, a switch actuating lever pivoted on said hoist body, an operating member pivoted to said switch actuating lever and to said chain guide for moving said switch actuating lever upon sliding movement of said chain guide on said support means, and spring means resisting sliding movement of said chain guide in one direction on said support means.

3. In a hoist of the class described, a hoist body, a chain actuator, a chain guide having a through passage for guiding a chain as it is moved longitudinally past said guide by said actuator, a pair of rods pivoted on said hoist body for swinging movement, bearing means secured to opposed portions of said chain guide and slidably mounted on said rods, the pivotal movement of said rods and the mounting of said bearing means thereon aligning said chain guide with the chain actuator and the load in all positions of the load, spring means yieldingly maintaining said bearing means in one end relation to said rods, switch actuating means moved by sliding movement of said chain guide and bearing means on said rods, and means mounting

said switch actuating means on said hoist body independently of said rods..

4. In a hoist of the class described, a hoist body, a chain guide having a through passage for the movement of a chain, a rod pivoted on said hoist body, means slidably mounting said chain guide on said rod, a limit switch on said hoist body, a limit switch actuating lever movably mounted on said hoist body, an operating member pivoted to said switch actuating lever and to said chain guide for moving said switch actuating lever upon sliding movement of said chain guide on said rod, and spring means resisting sliding movement of said chain guide in one direction on said rod.

5. In a hoist of the class described, a hoist body, a support rod pivoted on said hoist body and hanging vertically downwardly relatively to said hoist body when said hoist body is supported in its normal operating position, a chain guide, means slidably mounting said chain guide on said rod, a limit switch on said hoist body, a limit switch actuating lever movably mounted on said hoist body, an operating member pivoted to said switch actuating lever and to said chain guide for moving said switch actuating lever upon sliding movement of said chain guide on said rod, and spring means resisting sliding movement of said chain guide in one direction on said rod.

6. In a hoist of the class described, a hoist body, a chain actuator, a chain guide for guiding a chain as it is moved longitudinally past said guide by said actuator, support means mounting said chain guide for pivotal swinging movement on said body by said chain as said chain moves relatively to said guide, means mounting said chain guide for sliding movement relatively to said support means independent of the pivotal movement of said support means, the pivotal movement of said support means and the mounting of said chain guide thereon aligning said chain guide with the chain actuator and the load in all positions of the load, and switch actuating means mounted on said hoist body independently of said support means and moved by sliding movement of said chain guide on said support means.

7. In a hoist of the class described, a hoist body, a chain actuator, a chain guide for guiding a chain as it is moved longitudinally past said guide by said actuator, support means mounting said chain guide for pivotal swinging movement on said hoist body by said chain as said chain moves relatively to said guide, means mounting

said chain guide for sliding movement relatively to said support means independent of the pivotal movement of said support means, the pivotal movement of said support means and the mounting of said chain guide thereon aligning said chain guide with the chain actuator and the load in all positions of the load, spring means resisting sliding movement of said guide in one direction on said support means, switch actuating means moved by sliding movement of said chain guide on said support means against the pressure of said spring means, and means mounting said switch actuating means on said hoist body independently of said support means.

15 8. In a hoist of the class described, a hoist body, a chain, a chain actuator, a chain guide having a through passage for guiding said chain as it is moved longitudinally past said guide by said actuator, a rod pivoted on said hoist body, means slidably mounting said chain guide on said rod whereby said chain through the pivotal movement of said rod aligns said chain guide with a straight line passing from the load to the chain actuator in all positions of the load, means on 20 said chain for sliding said chain guide on said rod, and switch actuating means moved by sliding movement of said chain guide on said rod.

9. In a hoist of the class described, a hoist body, a chain, a chain actuator, a chain guide having a through passage for guiding said chain as it is moved longitudinally past said guide by said actuator, a rod pivoted on said hoist body, means slidably mounting said chain guide on said rod whereby said chain through the pivotal movement of said rod aligns said chain guide with a straight line passing from the load to the chain actuator in all positions of the load, spring means 35 resisting sliding movement of said chain guide on said rod, means on said chain that strikes the guide to move it relatively to said rod, and switch actuating means moved by sliding movement of said chain guide on said rod.
